(57) **CLAIM**

The ornamental design for a display panel for vehicles, as shown and described.

DESCRIPTION

1. Display panel for vehicles

1.1 : Perspective

1.2 : Front

1.3 : Back

1.4 : Left

1.5 : Right

1.6 : Top

1.7 : Bottom

1.8 : Reference

The broken lines indicate portions of the article that form no part of the claimed design; the dot-dashed lines in reproductions 1.1, 1.2, 1.3 and 1.8 define the boundaries and do not form no part of the claimed design; reproduction 1.8 is a reference view showing the claimed design installed into the vehicle; the broken lines showing of the vehicle interior in reproduction 1.8 is provided for the purpose of illustrating environmental structure and form no part of the claimed design.
